(57) **CLAIM**

I claim the ornamental design for a freezable hemorrhoid pain relief aid, as shown.

DESCRIPTION

FIG. 1 is a back side plan view of the freezable hemorrhoid pain relief aid of my design.

FIG. 2 is a left side plan view of the freezable hemorrhoid pain relief aid of my design.

FIG. 3 is a front side plan view of the freezable hemorrhoid pain relief aid of my design.

FIG. 4 is a top side plan view of the freezable hemorrhoid pain relief aid of my design.

FIG. 5 is an under side plan view of the freezable hemorrhoid pain relief aid of my design.

FIG. 6 is a right side plan view of the freezable hemorrhoid pain relief aid of my design; and,

FIG. 7 is a perspective view of the freezable hemorrhoid pain relief aid of my design.
